PAPER ROLL HOLDER

Laurence A. Wagner, Torrance, Calif.

Application June 8, 1934, Serial No. 729,587

6 Claims. (Cl. 242—55.2)

My invention relates to a paper roll holder for toilet paper rolls and the like.

The objects of my invention are:

First, to provide a very compact holder of this class for enclosing the paper roll and one which is very simple and economical of construction;

Second, to provide a device of this class in which the roll may be easily replaced, from which the paper may be easily withdrawn, and which will not readily get out of order;

Third, to provide novel and simple means for directing the free end of the paper downwardly from the device; and

Fourth, to provide novel means for mounting the holder so that it may be readily removed or detached from the securing means for loading the holder with a new roll.

With the above objects in view, I have devised a paper roll holder having certain novel features of construction, as will be hereinafter described in detail and particularly set forth in the appended claims, reference being had to the accompanying drawing which forms a part of this application, and to like characters of reference designating similar parts on the several views of the drawing, in which:

Fig. 1 is a partial front elevation and partial section of my paper roll holder in one form adapted for holding toilet paper, the sectional portion being taken on the line 1—1 of Fig. 2;

Fig. 2 is a fragmentary section thereof taken at 2—2 of Fig. 1;

Fig. 3 is a fragmentary section thereof taken at 3—3 of Fig. 1;

Fig. 4 is a fragmentary sectional elevation, similar to Fig. 2, of a slightly modified construction;

Fig. 5 is a fragmentary section thereof taken at 5—5 of Fig. 4;

Fig. 6 is a perspective view of another slightly modified form; and,

Fig. 7 is a fragmentary section thereof taken at 7—7 of Fig. 6.

The paper roll holder, shown in Figs. 1, 2, and 3, consists essentially of a supporting bracket 1 and a housing or cover 2. The bracket is in the form of a plate securable in any suitable manner to a wall, and having, at its upper and lateral edges, outwardly extending flanges 1a for locating the housing which is positioned over the same. At the lower ends of the lateral flanges are ears or journals 1b through which the lower portions of the side walls of the housing extends a rod 3 about which the hous-

ing is permitted to swing outwardly, as shown by dotted lines.

The housing is partially cylindrically shaped to conform substantially to the paper roll placed therein, the cylindrical portion 2a lying horizontally and the back side 2b being open, with the upper portion and the side walls 2c fitting against the outer sides of the flanges 1a. The rear portion of the housing extends below the cylindrical portion, and the side walls of this portion pivotally support the housing on the rod.

The engaging portions of the upper flange 1a and the housing are provided with interlocking depressions 1c and projections 2d, whereby the housing may be snapped into and held in a raised position.

On the inner sides of the side walls 2c are horizontal raised portions in which are horizontal slots 2e, at the forward, or inner ends thereof with respect to the housing, are notches or slight depressions 2f which are positioned substantially at the central portions of the side walls 2c. The bottoms of the slots and depressions are preferably flush with the inner sides of the side walls 2c. These depressions are oppositely positioned and are bearings for bearing pins 4a at the opposite ends of the roller 4 which supports the paper roll 5. When the housing is shifted about its pivotal axis to the position shown fragmentarily by dotted lines, the roller may be readily removed by sliding the pins from the slots 2e.

On the rod 3 are mounted a plurality of rollers 6, such as rubber, which are juxtaposed to or in engagement with a wall 1d extending forwardly at an angle from the lower edge of the wall plate 1, and preferably slightly resilient with respect to the rollers 6. On one end of the rod is a knob 7 for rotating the rollers 6 when desiring to feed the end of the paper downwardly, as shown. The paper is also held between the rollers 6 and the wall 1d to facilitate severing of the depending paper from that within the device.

The embodiment shown in Figs. 4 and 5 is the same as that described above except that in this instance the side flanges of the bracket or wall plate 1 are provided with downwardly inclined slots 1e forming hook portions, into which extend pins 8, carried by and extending inwardly from the side walls of the housing 2, for removably locking the housing on the wall plate.

In the modified structure shown in Figs. 6 and 7, the bracket or wall plate is omitted and the housing 2 provided on the side walls 2c, and adjacent the rear edges, with laterally extending ears 9 having slots extending upwardly from

the lower edges for supporting the housing on screws, as shown by dotted lines.

In this modification, there is also provided at the lower end an additional rod 18, parallel to the rod 3, and having thereon rollers 11 positioned preferably in engagement with the rollers 6, for feeding the paper downwardly.

Though I have shown and described a particular construction, and certain modifications thereof, I do not wish to be limited to this construction, nor to the modifications thereof, but desire to include in the scope of my invention the construction, combination, and arrangement substantially as set forth in the appended claims.

15 I claim:

1. In a device of the class described, a housing open at its back, a bracket for pivotally supporting the same with its open back against a wall, means for supporting a paper roll in the housing, and a feed roller rotatably mounted at the lower end of the housing, the bracket having a portion thereof forming an inclined wall resiliently directed toward the back of the roller for forcing paper from the roll against the roller.
2. In a device of the class described, a bracket securable to a wall at its back, a housing, a rod pivotally connecting the lower side of the housing to said bracket adjacent said back, said housing being detachably securable at its upper end to the upper end of the bracket, the housing having side walls extending forwardly of the bracket and having bearing depressions at the inner surfaces and substantially middle portion of the opposite side walls, and a paper roller rotatably mounted at its ends in said depressions, said rod having paper feed rollers thereon and so positioned opposite the lower portion of the bracket as to receive therebetween the end of the paper supported on the first roller.
3. In a device of the class described, a bracket securable to a wall at its back, a housing, a rod pivotally connecting the lower side of the housing to said bracket adjacent said back, said housing being detachably securable at its upper end to the upper end of the bracket, the housing having side walls extending forwardly from the bracket and also horizontal slots in the inner surfaces of said side walls, said slots extending forwardly from the bracket and provided at the forward ends thereof within the housing with slight depressions, and a paper roller rotatably mounted at its ends in said depressions, said rod having paper feed rollers thereon and so positioned opposite the lower portion of the bracket as to receive therebetween the end of the paper supported on the first roller.

4. In a device of the class described, a bracket securable to a wall at its back, a housing, a rod pivotally connecting the lower side of the housing to said bracket adjacent said back, said housing being detachably securable at its upper end to the upper end of the bracket, the housing having side walls extending forwardly from the bracket and also having horizontal slots in the inner surfaces of said side walls, said slots extending forwardly from the bracket and provided at the forward ends thereof within the housing with slight depressions, a paper roller rotatably mounted at its ends in said depressions, said rod having paper feed rollers thereon and so positioned opposite the lower portion of the bracket as to receive therebetween the end of the paper supported on the first roller, and a knob on the rod for manually rotating the rollers and feeding the paper.

5. In a paper roll holder, a bracket mountable on a wall, an open-back housing pivotally hung at the bottom of said bracket and provided on its inner side surfaces with depressions, a paper roller seatable in said depressions, feed rollers on the pivot of the housing, and resilient means on said bracket bearing against said feed rollers when the housing is mounted on the bracket to guide paper from said paper roller out of the housing.

6. A paper roll holder comprising, a wall bracket, an open-back housing, means pivotally combining said bracket and housing at the bottom, the housing above its pivot extending outwardly cylindrically to hold a roll of paper and provided with pockets for receiving the bearing pins of the paper roll, said pockets extending from the axial center of the housing to its open back in order to prevent dislodgment of the paper roll pins when the housing is closed, but being upwardly directed when the housing is swung outwardly on its pivot thereby to facilitate insertion of the paper roll bearing pins, a feed roller at the housing pivot, and a member projecting from the bracket for yielding contact with said feed roller.

7. In a device of the class described, a housing open at its back, a bracket for pivotally supporting the same with its open back against a wall, means for supporting a paper roll in the housing, and a feed roller coaxial with the pivotal axis of the housing and bracket, one of the latter having a portion resiliently directed toward the roller for forcing paper from the roll against the roller.
